ATTACHMENT FOR HOSIERY KNITTING MACHINES

Earl Margerison, Elkins Park, Pa., assignor to
Northwood Hosiery Co., Philadelphia, Pa., a
corporation of Pennsylvania

Application August 30, 1935, Serial No. 38,628

8 Claims. (Cl. 66—82)

This invention relates to an attachment for a flat full fashioned hosiery knitting machine for controlling the stitch-regulating mechanism thereof, automatically, to produce hosiery in accordance with the disclosure of my copending application for a Stocking bearing Serial No. 33,362 and filed under date of July 26, 1935, wherein the stitches in the courses constituting the knee area are gradually decreased in length from that of those employed in the upper welt section of the stocking to that of those employed in the lower or calf section of the stocking.

The object of the present invention is to provide mechanism which may be readily applied to existing full fashioned hosiery knitting machines of well-known makes and which can be controlled by the regular narrowing or pattern chains of such machines to operate the stitch-regulating means periodically to change the length of stitch in each successive course within the knee area or for each group of a series of groups of courses respectively composed of a plurality of courses wherein all the stitches are of equal lengths.

The construction, application and operation of the device forming the subject matter of the present invention will be fully disclosed hereinafter, reference being had to the accompanying drawings, of which:

Fig. 1 is a perspective view illustrating the device as applied to the stitch-regulating mechanism of a conventional machine;

Fig. 2 is a fragmentary front elevation of the narrowing motion and pattern chain of said machine and the controlling mechanism of the device forming the subject matter of the present invention;

Fig. 3 is a front elevation of the device as applied to the regular stitch-regulating mechanism of the machine;

Fig. 4 is a sectional elevation taken on the line 4—4, Fig. 3;

Fig. 5 is a sectional plan view taken on the line 5—5, Fig. 4; and

Fig. 6 is a diagrammatic view of the stocking.

As shown in Fig. 1 of the drawings, 1, 1 are the needles of one section of a conventional type of flat full fashioned hosiery knitting machine. The needle bar, in which said needles are rigidly mounted, is shown at 2. The needle bar 2 is pivotally mounted on and at the outer ends of a pair of laterally spaced levers 3, only one of which is shown in the present instance. The needle bar levers 3, 3 are secured to the needle bar shaft 5 which is mounted for oscillation in the main frame of the machine and rocked by cams (not

shown) on the main cam shaft 6 of the machine.

The needle bar 2 is rocked on the levers 3, 3 by a depending arm 7, through a link 8, from a presser lever 9 which is secured to the presser shaft 10 of the machine and which, like the needle bar 9, is mounted for oscillation in the main frame of the machine.

The presser arm 9 has a cam follower 11 thereon which is engaged by the presser cam 12 on the cam shaft 6, for rocking the needle bar to effect pressing of the needles against the presser plate (not shown) as the shaft 5 is rocked to lower the needles to cast their stitches in the well-known manner.

As is well-known the length of the stitch is determined by the distance at which the shanks of the needles are held away from the forward edges of the sinkers and dividers of the machine (not shown) while the thread is being fed to and sunk around and between the needles.

This positioning of the needles relative to the sinkers and dividers and the consequent length of the stitches is controlled by a lever 14, on the stitch-regulating shaft 15, which has a laterally projecting pin 16 engaging the lower end of the presser lever 9 and which holds the cam roller 11 off the presser cam 12 during the laying of the thread to the needles.

The stitch-regulating shaft 15 is pivotally mounted in bearings 16 on the front beam 17 of the machine and is maintained in stitch-measuring position by a circular portion 18 of a cam 19 on the main cam shaft 6 while the thread carrier and slur cock of the machine are traversing the needle and sinker banks respectively and until the dividers have been advanced by the catch bar to equalize the thread between the needles, said cam being cut away at 20 to permit the presser cam to function.

The cam 19 is engaged by cam follower 21 which is carried by the outer end of the one part 22 of the composite stitch-regulating lever 23, the second part 24 of which is bifurcated and secured to the stitch-regulating shaft 15, while the part 22 is loosely mounted on said shaft intermediate the hubs 25 and 26 of the lever part 24.

The length of the stitch is determined by varying the angle between the two parts 22 and 24 of the composite lever 23 about the common axis of both which is coincident with the axis of the regulating shaft 15. This is normally accomplished manually to set the machine for a given number of courses per inch by actuating the setting or slackening lever 27.

The slackening lever is secured to a coarse

threaded screw 28 which is threaded into a nut bearing 29 forming part of the lever part 24. The coarse screw 28 is bored axially and said axial bore is threaded for the reception of a vernier screw 30, the inner end of which bears against a pad 32 which is carried by the lever part 22. The vernier screw 30 is provided at its opposite end with an index wheel 33.

The index wheel 33 is provided with transverse notches on its periphery with which is engaged a spring-pressed detent 34 which is housed in the slackening lever 27.

The slackening lever is provided with a second detent 35 which engages the teeth or notches of an index disc 36 which is secured to the outer end of the nut bearing 29.

By turning the slackening lever 27, notch after notch around the index disc 36, a relatively large variation in the angle between the two lever parts 22-24 is accomplished for each notch and by turning the vernier screw 30, a very slight variation in said angle is effected for each notch on the index wheel 33, due to the slight angle of the threads of the screw 30.

25 The machine as so far described is of the usual and ordinary construction and operates in the usual conventional manner.

The stocking shown in Fig. 6 and covered per se by the above noted copending application differs from an ordinary stocking in that the length of the stitches in the courses constituting the knee area C changes gradually from the longer length of stitch employed in the welt or top sections A and B of the stocking to the shorter length stitch 35 employed in the leg section D.

To accomplish the above noted gradual shortening of the length of stitch automatically, the outer end of the vernier screw 30 is provided with a ratchet wheel 40, which as the composite lever 40 23 is rocked outwardly by the cam follower 21 riding from the low part 20 to the high part 18 of the cam 19, is engaged by a pawl 41 which is pivotally mounted on a stud 42 secured in and projecting outwardly from the front beam 17 of the machine.

Each time the lever 23 rocks outwardly the vernier screw 30 is turned to the extent corresponding to the angle between each two or more teeth of the ratchet wheel 40, thus a very slight variation in the angle between the two lever parts 22-24 is accomplished with a resultant very slight change in the length of the stitches of the course which is made following the turning of the vernier screw 30.

55 In some instances, it may be desirable to change the length of stitch in each succeeding course in the knee area C but it is preferable to change the length of stitch in each of a number of groups of courses, such, for example, as after each second, third, fourth or fifth course and so on. Variation of the stitch length at every fourth course, however, has proven quite satisfactory in practice, and the change between each succeeding group of four courses is so gradual that it cannot be detected by other than close inspection by an expert, thus as the change in stitch length takes place gradually over a relative large area of the stocking the general appearance of the stocking is in no wise affected while a considerably greater elasticity is provided in the knee area than has been possible heretofore without affecting the appearance of the stocking.

In order to make the pawl 41 effective at every fourth course, or at any desired interval, the 75 regular pattern or narrowing chain 45 of the

machine is provided with relatively spaced buttons 46, 46 which, as the chain is advanced link by link in the usual and ordinary manner, engage a lug 47 on a lever 48 which is pivotally mounted at 49 on the main bracket 50 of the regular chain motion of the machine.

The lever 48 is connected by a reach rod or link 51 to a depending extension 52 of the pawl 41.

The pawl 41 is normally maintained in an inactive position, out of the path of oscillation of the ratchet wheel 40 as the lever 23 rocks about the axis of the regulating shaft 15, by a spring 53 (see Fig. 2) having one end secured to the rod 51 and its opposite secured to a fixed portion of the machine.

The connection between the rod 51 and the pawl extension 52 is of a resilient nature, said rod having a collar 54 secured thereto at one side of the pawl extension 52 and arranged to engage one side of said extension as the rod moves in the direction to effect disengagement of the pawl 41 from the ratchet wheel 40, and a spring 55 encircling the rod 51 between the opposite side of the extension and a second collar 56 secured to the rod 51 for resiliently pressing the pawl into engagement with the ratchet wheel 40, said rod passing through the pawl extension 52 and being capable of sliding movement therein.

In order to maintain the pawl 41 in alignment with the ratchet wheel 40 at all times, as the composite lever 23 rocks about the axis of the regulating shaft 15, the pawl 41 is composed of two parts 41a and 41b pivotally connected at 41c for relative movement about an axis disposed at right angles to the axis of the pivot stud 42, and the section 41b is provided with a pair of fingers 57, 57 which are disposed at opposite sides respectively of the ratchet wheel 40 so that as the plane of the ratchet wheel changes the pawl section 41b follows by pivotal movement relative to the section 41a about the hinge axis 41c.

Normally, the extent of rocking of the ratchet wheel 40 about the axis of the regulating shaft would be greater than the maximum single movement of the ratchet wheel and in order that the ratchet wheel will receive but a one, two or three etc. tooth racking for each oscillation of the lever 23 the pawl 41 is provided with a cam surface 60 which is adapted to be engaged by a pin 61. The pin 61 is adjustably carried by the lever 23 and which, as said lever is rocked, holds the pawl out of contact with the ratchet wheel, permitting such engagement only as the lever 23 rocks to an extent where the pin 61 functioning as a cam follower slides down the incline of the cam 60 on the pawl and thereby causes the pawl to engage the ratchet wheel during the last part of the rocking motion which is just sufficient to effect the desired degree of racking of the ratchet wheel 40.

By the above noted construction, the vernier screw 30 is given a very slight degree of rotation and the angle between the lever parts 22 and 24 is varied very slightly, consequently the length of stitch is varied to a very slight extent each time a change therein occurs.

In cases where the stocking is being knitted from the top toward the foot the stitches are gradually decreased in length, but in cases where the stocking is knitted from the toe toward the top the stitches in the knee area would be gradually lengthened.

After the completion of each set of stockings on the knitting machine, the vernier screw 30 is returned to the starting point, by means such

as a knob 65 secured to the outer end of said screw, for setting the machine to the length of stitch required for the starting ends of the stockings of the next set.

5. I claim:

1. The combination with variable stitch-regulating means of a knitting machine which includes a composite lever structure comprising a pair of sections, cooperating nut and screw elements carried by said lever for varying the angle between said sections, and means for intermittently turning one of said elements relative to the other consistently in one direction for gradually decreasing the angle between said lever sections, producing a corresponding gradual reduction in the length of stitch produced by said machine.

2. The combination with variable stitch-regulating means of a knitting machine which includes a composite lever structure comprising a pair of sections, cooperating nut and screw elements carried by said lever for varying the angle between said sections, and means including pawl and ratchet mechanism for intermittently turning one of said elements relative to the other consistently in one direction for gradually decreasing the angle between said lever sections, producing a corresponding gradual reduction in the length of stitch produced by said machine.

3. The combination with variable stitch-regulating means of a knitting machine which includes a composite lever structure comprising a pair of sections, cooperating nut and screw elements carried by said lever for varying the angle between said sections, and means including pawl and ratchet mechanism and means for controlling the engagement of the pawl with the ratchet for intermittently turning one of said elements relative to the other consistently in one direction for gradually decreasing the angle between said lever sections, producing a corresponding gradual reduction in the length of stitch produced by said machine.

4. The combination with variable stitch-regulating means of a knitting machine which includes a composite lever structure comprising a pair of sections, cooperating nut and screw elements carried by said lever for varying the angle between said sections, means including pawl and ratchet mechanism for intermittently turning one of said elements relative to the other for gradually varying the length of stitch produced by said machine, and a cam and cam follower carried by said pawl and said lever respectively for controlling the engagement of the pawl with the ratchet.

5. The combination with variable stitch-regulating means of a knitting machine which includes a composite lever structure comprising a

pair of sections, cooperating nut and screw elements carried by said lever for varying the angle between said sections, means including pawl and ratchet mechanism for intermittently turning one of said elements relative to the other for gradually varying the length of stitch produced by said machine, a cam and cam follower carried by said pawl and said lever respectively for controlling the engagement of the pawl with the ratchet during a portion of a rocking motion of said lever, and means for controlling the time of engagement between said cam and cam follower.

6. The combination with variable stitch-regulating means of a knitting machine which includes a composite lever structure comprising a pair of sections, cooperating nut and screw elements carried by said lever for varying the angle between said sections, means including pawl and ratchet mechanism for intermittently turning one of said elements relative to the other for gradually varying the length of stitch produced by said machine, a cam and cam follower carried by said pawl and said lever respectively for controlling the engagement of the pawl and the ratchet, and means actuated by the pattern chain of said machine for controlling engagement between said cam and the cam follower.

7. The combination with variable stitch-regulating means of a knitting machine which includes a composite lever structure comprising a pair of sections, cooperating nut and screw elements carried by said lever for varying the angle therebetween, means including pawl and ratchet mechanism for intermittently turning one of said elements relative to the other consistently in one direction for gradually decreasing the angle between said lever sections, producing a corresponding gradual reduction in the length of stitch produced by said machine, and means controlled by the pattern chain of the machine for controlling engagement between said pawl and ratchet.

8. The combination with variable stitch-regulating means of a knitting machine which includes a composite lever structure comprising a pair of sections, cooperating nut and screw elements carried by said lever for varying the angle between said sections, means including pawl and ratchet mechanism for intermittently turning one of said elements relative to the other for gradually varying the length of stitch produced by said machine, said pawl comprising two pivotally connected parts, means pivotally mounting one part to a fixed portion of the machine, and means for maintaining the second part in operative alignment with said ratchet.

EARL MARGERISON.
